UNITED STATES PATENT OFFICE.

GEORGE J. KOCIALEK, OF AVOCA, PENNSYLVANIA.

AERIAL TORPEDO.

1,275,445.

Specification of Letters Patent. Patented Aug. 13, 1918.

Application filed March 22, 1918. Serial No. 223,941.

To all whom it may concern:

Be it known that I, GEORGE J. KOCIALEK, a citizen of the United States of America, residing at Avoca, in the county of Luzerne 5 and State of Pennsylvania, have invented certain new and useful Improvements in Aerial Torpedoes, of which the following is a specification.

The primary object of the invention is the provision of a torpedo adapted for traveling through the air by its own power to be automatically exploded when striking any object such as a point within the enemies' lines.

A further object of the invention is to provide a flying torpedo adapted to be directed in its travel toward the enemy, the same having self-contained propelling means and arranged to automatically explode for destroying the enemies' men and property.

A still further object of the device is to provide a flying torpedo having a launching device for directing the travel of the torpedo, motor means being arranged within the torpedo separating the same from the launching device when released and carrying the torpedo through the air toward a target such as the trenches of the enemy.

In the drawings forming a part of this application and in which like designating 30 characters refer to corresponding parts throughout the several views,

Figure 1 is a side elevation of the torpedo and its launching device, a portion of the latter being shown in vertical section.

Fig. 2 is a top plan view thereof.

Fig. 3 is a central longitudinal sectional view of the torpedo.

Fig. 4 is a transverse sectional view taken upon the line IV—IV of Fig. 1.

Fig. 5 is a rear end elevation of the torpedo and its fin members.

Fig. 6 is an elevational view of a portion thereof, and

Fig. 7 is a sectional view taken upon the line VII—VII of Fig. 1.

The device broadly consists of a bomb or torpedo 10 having a directing means or fin device 11 carried thereby while a launching

means 12 is arranged for starting the torpedo upon its course through the air.

The torpedo 10 comprises a cylindrical casing 13 with a rounded forward end 14 and a removable cap 15 at its open rear end while a shaft 16 is eccentrically journaled longitudinally of the casing 13 with a propeller blade 17 upon its outwardly projecting end forwardly of the torpedo. A motor 18 is arranged within the central compartment or chamber 19 of the casing 13 adapted for operation by means of compressed air stored in the container or bottle 20 and communicating with the motor 18 through a pipe 21 having a controlling valve 22 arranged with a pull cord 23 extending to a point rearwardly of the cap 15 and having a handle 24 arranged adjacent thereto. The motor 18 is operatively connected by a train of gears 25 with a sleeve 26 through which the shaft 16 is splined.

Charges of explosive material 27 and 28 are arranged forwardly and rearwardly respectively of the compartment 19, a firing cap 29 being arranged for the charge 27 and a similar cap 30 being provided to explode the rear charge 28. A firing pin 31 is normally arranged spaced from the cap 30 having a head 32 positioned rearwardly of the cap 15 so that upon striking an object when the torpedo is moving with the cap 15 in the advance of the device, the cap 30 will explode the charge 28. A rod 33 is slidably arranged within the casing 13 having a foot member 34 within the charge 28 and having a forward sharpened end 35 normally arranged spaced from the cap 29. When the charge 28 explodes, the rod 33 is longitudinally projected for exploding the cap 29 and firing the forward charge 27.

A lever 36 is connected to the pin 31 and has an operating rod 37 positioned in alignment with the shaft 16 so that the shaft 16 will move rearwardly, contacting the rod 37 and bring the pin 31 into firing contact with the cap 30 when the propeller 17 hits against any object during the forward movement of the torpedo 10. From this con-

struction, it will be seen that both of the charges 27 and 28 within the torpedo will be automatically fired successively in whichever direction the torpedo may travel, such 5 explosion being adapted for damaging the surrounding objects.

The directing or fin device 11 comprises arcuate plates 38 and 39 hinged together as at 40 for encircling the casing 10 and set 10 cured thereon by locking means 41 which connect the said plates together in close contact with the casing 13. Radially arranged blades 42 are carried by the plates 38 and 39 which act during the flight of the torpedo 15 through the air somewhat after the nature of supporting and directing planes and giving a substantially straight course to the torpedo during its flight while pulled forwardly by the propeller 17.

20 The launching device 12 comprises a frame 43 mounted upon rails 44 positioned upon the ground, the said frame being adjustable and adapted for folding when desired having retaining struts 45 and 46 for arranging 25 the frames substantially upright when desired for use. A barrel member 47 is hinged as at 48 upon the top of the frame 43 having a four-armed receiving guide 49 arranged centrally of the barrel for receiving the torpedo 10 and fin members 11 thereon for initially starting the device upon its travel through the air.

A toothed rack 50 depends from the rear end of the barrel 47 for engaging a bracket 35 51 whereby the barrel may be tilted at different adjustments for starting the torpedo upon its flight at the required upward inclination. A retaining latch or trigger 52 is pivoted upon the rear end of the barrel 37 40 for engaging a lug 53 upon the rear end of the torpedo 10 for preventing the forward movement of the torpedo out of the barrel 47 until the trigger 52 is released.

With the torpedo and fin member arranged 45 in the barrel 47 ready for launching as illustrated in Figs. 1 and 2 of the drawings, the operator by pulling the handle 24 and opening the valve 22 will start the motor 18 in operation for rapidly revolving the propeller 17. When sufficient speed has been acquired 50 by the propeller to draw the torpedo 10 forwardly, the latch trigger 52 will be released whereupon the propeller 17 will forwardly draw the torpedo 10 and fin members 11 out 55 of the barrel 47 and through the air toward the place where the same has been directed by the person in charge of the device. The manner of exploding the charges 27 and 28 has already been fully described herein and 60 it will be seen that a self-propelled aerial torpedo is arranged, in which the direction of its course may be substantially controlled by manipulating the launching device 12. The entire device is preferably formed of

metal and a suitable form of propeller 17 is 65 adapted to be employed which may have a centrally arranged head 54 at the forward end of the shaft 16 for striking an object during the forward travel of the torpedo.

What I claim as new is:

70

1. An aerial torpedo comprising a casing, a shaft journaled through the casing adapted for inward longitudinal movement upon striking an object, a propelling fan for the device upon the outer end of the shaft, a 75 driving motor for said shaft arranged within the casing, starting means for the motor rearwardly of the casing, an explosive charge within the casing and means adapted for igniting the said charge upon the inward 80 reciprocation of the said shaft.

2. An aerial torpedo comprising a casing, a shaft journaled through the casing adapted for inward longitudinal movement upon striking an object, a propelling fan for the 85 device upon the outer end of the shaft, a driving motor for said shaft arranged within the casing, starting means for the motor rearwardly of the casing, an explosive charge within the casing, a firing pin for said charge 90 extending rearwardly of the casing adapted for igniting the charge upon an inward movement of the pin arranged within the inward path of movement of said shaft whereby the said charge is exploded when the outer 95 end of the shaft strikes an object during the forward movement of the device.

3. An aerial torpedo comprising a casing, a shaft journaled through the casing adapted 100 for inward longitudinal movement upon striking an object, a propelling fan for the device upon the outer end of the shaft, a driving motor for said shaft arranged within the casing, starting means for the motor rearwardly of the casing, an explosive charge 105 within the casing, a firing pin for said charge extending rearwardly of the casing adapted for igniting the charge upon an inward movement of the pin arranged within the inward path of movement of said shaft whereby the said charge is exploded when the outer 110 end of the shaft strikes an object during the forward movement of the device, a second and forwardly positioned explosive charge within the casing, an explosive cap for said forward charge, an exploding rod for the said cap having a foot portion arranged within the first named explosive charge whereby the forward charge is adapted 115 for automatic ignition subsequent to the igniting operation of the said firing pin.

4. An aerial torpedo comprising a casing, a shaft journaled through the casing adapted for inward longitudinal movement upon striking an object, a propelling fan for the device upon the outer end of the shaft, a driving motor for said shaft arranged within the casing, starting means for the motor rear- 120 125

wardly of the casing, an explosive charge within the casing, a firing pin for said charge extending rearwardly of the casing adapted for igniting the charge upon an inward movement of the pin arranged within the inward path of movement of said shaft whereby the said charge is exploded when the outer end of the shaft strikes an object

during the forward movement of the device, arcuate cover plates longitudinally secured around the said casing, and radially projecting sustaining planes carried by the said plates.

In testimony whereof I affix my signature.

GEORGE J. KOCIALEK.
